UNITED STATES PATENT OFFICE.

GEORGE D. HUNTER, OF BLOOMINGTON, INDIANA, ASSIGNOR TO
SULLIVAN MACHINERY COMPANY, OF CLAREMONT, NEW
HAMPSHIRE, A CORPORATION OF MAINE.

DIRECT-ACTING ENGINE.

No. 842,150.

Specification of Letters Patent.

Patented Jan. 22, 1907.

Application filed September 1, 1904. Serial No. 222,974.

To all whom it may concern:

Be it known that I, GEORGE D. HUNTER, a citizen of the United States, residing at Bloomington, Indiana, have invented an Improvement in Direct - Acting Engines, of which the following description, in connection with the accompanying drawings, is a specification, like letters on the drawings representing like parts.

10 My invention consists in improvements in direct-acting engines, being more particularly concerned with "chopper engines" intended for application to stone - channeling machines.

15 My invention relates particularly to means for maintaining the desired upstroke or lift to the piston travel and for permitting the use of a heavy or light lift to the piston as may be required with the varying conditions 20 of use.

In my present invention I have applied to a direct-acting engine a regulating device whereby the area of the exhaust-port leading from the head or upper end of the cylinder 25 may be throttled to any desired extent wholly independently of the action of the controlling valve or valves and also without effect upon either of the admission-passages or upon the remaining exhaust-passage leading from the opposite or tool end of the cylinder. By this means the pressure which is 30 caught in the head end of the cylinder on the return piston-stroke through its inability to escape out of the throttled exhaust-passage forms a cushion, against which the piston strikes on its upstroke after release of the tool from the stone and by which it is gradually brought to rest without injury to the cylinder-head or other part thereof. By decreasing the throttled area the travel of the 35 upstroke of the piston may be shortened and by increasing the area the travel may be lengthened. Since this does not affect the action of the controlling valve or valves, the 40 latter may be adjusted in their most effective position and the full power of the engine developed, if desired, both in delivering the blow and in withdrawing the tool from the cut, irrespective of the controlled length of 45 travel. Moreover, the regulator may be adjusted to correspond to the lift which varying conditions will require. Since the controlling valve or valves operate independ-

55 ently of the regulator, the latter may be adjusted to give the cylinder the benefit of the entire area of the exhaust-port or any portion thereof, and the engine, therefore, without the alteration of any part thereof may be employed where no variable regulation of the piston lift is necessary.

60 My invention will be best understood by reference to the following description, when taken in connection with the accompanying illustration, of one specific embodiment thereof, while its scope will be more particularly pointed out in the appended claims.

In the drawings, Figure 1 is a longitudinal section, partly broken away, of an engine embodying one form of my invention and showing the main piston-controlling valve, 70 together with head-end exhaust-passage controlled as herein described. Fig. 2 is a sectional plan view on the line 2 2 in Fig. 1, showing the exhaust-regulators.

Referring to the drawings, the cylinder *a* 75 has slidably therein a usual form of piston *b*, connected to the piston-rod *c*, the outer end of which (not shown) is adapted to be directly connected to a tool or a part carrying a tool, such as the reciprocating tool-carrying 80 cross-head of a chopper-engine.

The tool end of the cylinder has suitable 85 separate and independent admission and exhaust passages *d* and *e*, respectively, and the head end thereof is also provided with separate and independent admission and exhaust passages *f* and *g*, respectively, the said admission and exhaust passages at both ends 90 of the cylinder communicating independently of one another with the cylinder and the steam chest and exhaust. The said passages lead through the valve-plate *h* into the steam-chest *i*, wherein communication between the same and suitable admission-ports 95 *j* and a centrally-located exhaust-port *k* is controlled by a balanced piston-valve *l*, located in a chamber between the buffers *m* and *o*.

The piston-valve may be operated in any 100 desired way—as, for example, by the use of additional reversing and cut-off valves, the latter being ordinarily connected to and operated by the engine cross-head and acting to admit steam between ends of the piston-valve *l* and the buffers to move the said 105 valve at appropriate times and also properly

to cut off the admission of steam from the admission-ports *j*. This type of engine and this construction of reversing and cut-off valves are well known; but a knowledge thereof is unnecessary to an understanding of my present invention, and I have not illustrated the same herein.

Referring more particularly to Fig. 2, I have shown means for varying the capacity of the head-end exhaust-port *g*, such means comprising the regulating-screw *p*, which enters the side of the valve-plate *h* and may be adjusted to any desired position and acts to vary the available opening from the head end of the cylinder to the atmosphere, a lock-nut *q* being employed, if desired, to set the same in any selected position until readjustment is desired, which may be effected in any desired way, as by a handle (not shown) applied to the projecting end of the screw.

In the engine herein shown there is also employed a regulating-gate *r*, which herein is a valve lying across the exhaust-passage in the lower part of the steam-chest *i* and adapted to be turned by means of the outwardly-projecting stem *s* to intercept more or less the exhaust from the tool-end exhaust-passage *e*, and thereby to cushion the blow on the working piston-stroke should the tool miss or fall short of the work. The stem *s* on the gate *r* is provided with a lever *t*, through which the said gate *r* may be controlled by the operator at will during the operation of the engine and to conform to the varying requirements of the work.

The operation of the engine herein described is as follows: The controlling-valves being adjusted to their most effective or any desired position, the steam, which is herein assumed, for the sake of illustration, to be the motive power, is admitted to the chopper-engine cylinder, and the pressure enters the admission-port *f* at the head end of the cylinder and forces the piston downwardly to give the working stroke to the drill or other tool attached thereto. Should the tool miss or fall short of its work, the blow may be cushioned by the steam caught in the bottom of the cylinder, the cushioning effect of which may be regulated by the adjustable gate *r*. On the return stroke, after release of the tool, the piston is brought to rest by the steam throttled and caught in the upper end of the cylinder, and the amount of lift or upstroke will therefore be determined by the position of the regulating and throttling screw. If the piston has too much lift or upstroke, the regulating-screw is then turned inwardly until it throttles the exhaust-steam from the top of the piston in the cylinder to an extent necessary to give the desired lift or upstroke. If lift or upstroke is wanting, the regulating-screw is then turned outwardly to open up a larger area to the atmosphere, thus relieving the pressure of steam over the

top of the piston sufficiently to increase the piston lift. It will be noticed that this method of varying the lift of the piston does not affect the power which may be given to the upstroke, but that as great power may be developed upon the upstroke with a shorter lift as with a longer one.

It will be obvious that my invention may be widely varied in form, detail, and arrangement of parts, unnecessary here to recite, from the embodiment by which I have herein illustrated the same; but it is to be understood that these changes and modifications, as well as others which will be obvious to those skilled in the art, are included within the scope of my invention.

I claim—

1. A direct-acting engine for stone-channelling machines or the like, comprising a cylinder, a piston movable therein, a piston-rod adapted to be connected directly to a drill or other tool, admission and exhaust passages independently communicating with the steam chest and exhaust and with the head end and tool end of said cylinder, valved means for controlling the admission to and exhaust from both ends of said cylinder, a valve for varying the area of the exhaust-passage in the head end of the cylinder, mounted for movement transversely of the exhaust-passage to regulate the exhaust independently of the admission-passage and its controlling-valve to thereby control the inward stroke of the piston after release of the tool, and an adjustable gate in the exhaust-passage in the tool end of the cylinder, to regulate the exhaust in said tool end independently of the admission-passage and its controlling-valve to thereby control the working or outward stroke of the piston.

2. A direct-acting engine for stone-channelling machines or the like, comprising a cylinder, a piston movable therein, a piston-rod adapted to be connected directly to a drill or other tool, admission and exhaust passages independently communicating with the steam chest and exhaust and with the head end and tool end of said cylinder, valved means for controlling the admission to and exhaust from both ends of said cylinder, a valve mounted for movement transversely of the exhaust-passage in the head of the cylinder to regulate the exhaust independently of the admission-passage and its controlling-valve to thereby control the inward stroke of the piston after release of the tool, and an adjustable gate in the exhaust-passage in the tool end of the cylinder, to regulate the exhaust in said tool end independently of the admission-passage and its controlling-valve to thereby control the working or outward stroke of the piston.

3. A direct-acting engine for stone-channelling machines or the like, comprising a cylinder, a piston movable therein, a piston-rod

adapted to be connected directly to a drill or other tool, admission and exhaust passages independently communicating with the steam chest and exhaust and with the head 5 end and tool end of said cylinder, valved means for controlling the admission to and exhaust from both ends of said cylinder, a regulating-screw mounted for longitudinal movement transversely of the exhaust-passage 10 in the head of the cylinder to vary the area thereof, whereby the exhaust may be regulated independently of the admission-passage and its controlling-valve to thereby control the inward stroke of the piston after release of the tool, and an adjustable gate in 15 the exhaust-passage in the tool end of the cylinder, to regulate the exhaust in said tool end independently of the admission-passage and its controlling-valve to thereby control the working or outward stroke of the piston. 20

In testimony whereof I have signed my name to this specification in the presence of two subscribing witnesses.

GEORGE D. HUNTER.
